UNITED STATES PATENT OFFICE

FRANK MARION, OF BARRE, VERMONT, ASSIGNOR TO GREEN MOUNTAIN OIL BURNER CORPORATION, OF ST. JOHNSBURY, VERMONT, A CORPORATION OF VERMONT

OIL BURNER

Application filed March 7, 1929. Serial No. 345,197.

The invention relates to improvements in oil burners, particularly of the retort type in which the liquid fuel is admitted to a bowl-like retort structure and means provided for directing heated air thereupon in a manner to effect mixture of the vapor and air for efficient combustion. It is an important aim of the invention to present novel means for effecting the movement of the mixture of fuel and air to the end that a thorough commingling of the two may be effected. At the same time, while attaining this purpose, it is an advantage of the invention that the parts are extremely simple and adapted to 10 be assembled by simple superposition of the parts. Another object is to effect a novel coordination of movement of admitted air entering the burner with respect to the oil fuel to enhance the efficiency of distribution of 20 the oil upon heating surfaces, and consequent vaporization of the fuel. Another important aim of the invention is to enable the presentation of a device having these advantages while at the same time enabling the retention 25 in a simple form of the usual safety features. A further important aim is to so construct the device that it may be readily taken apart and cleaned without the use of tools in the 30 operation, and without disturbing the fuel connections.

Additional objects, advantages and features of invention reside in the construction, arrangement and combination of parts involved in the production of the invention, as 35 may be readily understood from the following description and accompanying drawings, wherein

Figure 1 is a vertical sectional view of a burner constructed in accordance with my invention.

Figure 2 is a top view thereof, with parts broken away.

Figure 3 is a section on the line 3—3 of Figure 2.

There is illustrated a burner comprising a bowl section 10, which—while shown as of circular form—may be made in any other forms as desired, this bowl at one point having a sleeve or hollow lug 11 on the lower 50 side receiving adjustably a supporting leg

12, the foot plate 12' of which is adapted to be set upon a grate for support of the burner within the fire-box, as will be understood. The leg 12 is held in adjusted position on the burner by a set screw 13 engaged through 55 the side of the sleeve 11. A central opening is formed through the bowl, having a downwardly extending nipple 14, which receives the upturned end of an air-pipe 15 which is customarily led from any usual blower device, formally illustrated at 16. The bowl is in the form of a somewhat shallow basin, and is formed with a concentric oil groove 16 in close and circumscribing relation to the opening through the center of the bowl. An 60 oil supply pipe 17 is connected into the bottom of this groove from below the bowl, and any usual supply connection made with a reservoir and control valve automatic or hand controlled, as may be desired. The bowl proper 65 terminates at the extremity of its outwardly sloping and upwardly curved bottom at 18. Just outwardly of this a further integral extension of the bowl is formed, as an annular trough 19, having an outer side higher than 70 the lip or perimetral termination of the bowl proper at 18, (as may be seen in Figure 1). An overflow pipe 20 is led from the bottom of 75 this trough 19 at a suitable point, and may be conducted to any safety devices to stop 80 the flow of fuel through the pipe 17, as is familiar in such devices.

The air from the conduit 15 passing upwardly through the bowl is received by an air distributing chamber structure there- 85 above formed in two parts, a lower jet plate 21 forming the bottom of the chamber, and a top piece or cap 22 forming the upper part thereof. The plate 21 is circular in form, having a central opening therethrough from 90 which there is extended downwardly an integral tube or nipple 23, adapted to set snugly or removably in the upper part of the nipple 14 of the bowl, which is extended 95 above the bowl to support the plate.

The cap 22 comprises a circular plate having a depending peripheral flange 24; and a series of legs 25 adapted to rest upon the plate 21 and secured thereto by screws 25' support the flange 24 in spaced relation to the plate 100

21. The plate 21 is formed with a multiplicity of apertures 26, all of which have an inclination from above downwardly in a generally clockwise direction, as illustrated. By reason of this inclination, air admitted through the conduit 15 to the chamber and passing downwardly through the openings 26 will be given a clockwise movement in that portion of the bowl beneath the plate 21. Certain of the apertures 26 are so located as to direct the air passing therethrough into the oil groove 16 while the others are variously spaced outwardly thereof. Carried upon the depending flange 24 there is a multiplicity of curved vanes 28, which are extended downwardly so as to lie in a zone coincident horizontally with the slot 30 which is formed between the flange 24 and the plate 21. As a result of the provision of these vanes, air passing outwardly through this slot will be given a clockwise rotary movement, and this air will impinge upon the current passing outwardly from the bowl, and produce a flattening of the flame resulting when the mixture of air and fuel is ignited.

It will be seen that access to the interior of the air distributing chamber may be gained by simply removing the cap 22, and similarly complete access to all oil receiving and vaporizing channels in the bowl portion of the burner is attained by lifting off the plate 21 and nipple 23 of the air distributing chamber. This latter may be accomplished manually, as it is not necessary to remove the bowl part for access to oil passages for there are none which are not uncovered by removal of the parts described.

In case the burner is not made of circular form, the inclination of the vanes 28 may be varied, in order to produce the desired eddies and counter-currents to effect proper mixture, as required.

In the use of this device, when the mixture passing therethrough is ignited, the cap 22 and plate 21, as well as the bowl, become highly heated, and the fuel when admitted through the pipe 17 becomes quickly vaporized in the channel 16. Distribution of oil around the channel is facilitated by having certain of the jets 26 directed toward the channel so that the oil is propelled by air admitted from the point of entrance and around the channel. The vapor thus produced is quickly formed with the air admitted through the plate 21 into a primary mixture by the successive jets arranged radially, and the fact that they are inclined so that the entire body of mixture beneath the plate is moving orbitally results in each air jet projected from the plate 21 encountering fresh bodies of gas constantly, so that a thorough admixture is effected in this primary stage. The upwardly directed edge portion of the bowl then causes the outwardly passing mixture to move across the path of

air being ejected from the slot 30 and the element of radial movement in the air passing outwardly through the slot produces vertical eddies in the mixture moving outwardly from the bowl, while the clockwise movement induced by the vanes 28 results in the whole mass moving orbitally with a series of horizontal eddies in such closely spaced relation that each one at its outer part encounters oppositely moving masses of the eddy from the next adjacent vane, the whole maintaining an element of horizontal movement. This mixture being ignited, propagation of the flame occurs in this violently agitated radially moving portion, and partly under the plate 21, so that the latter and the bowl become highly heated. Consequently the air within the chamber above also becomes heated, and that portion passing outwardly through the slot is able to complete combustion efficiently, being heated by the vanes also.

It will be seen that the parts are adapted to be cast readily with simple molds and without requiring any cores, so that it may be produced at an extremely low cost. It may be assembled and installed with a minimum of labor or other expense and its repair and upkeep likewise made efficient.

I claim:—

1. A burner of the character described comprising a bowl having a central air inlet opening and a circumscribing oil groove adjacent the opening, means for supplying oil to the groove, an air distributor chamber communicating with the air inlet opening and comprising a lower plate adapted to be supported over the bowl and having a plurality of apertures which are inclined from above downwardly in a generally clockwise direction, and a cap member set thereon having a depending peripheral flange spaced from the plate to form an air ejecting slot above the lip of the bowl.

2. The structure of claim 1 in which said cap is provided with a multiplicity of lateral vanes in the same horizontal zone with the slot shaped to produce turning effects on air passing from the slot.

In testimony whereof I affix my signature.
